UNITED STATES PATENT OFFICE

CHARLES F. PFLANZE, OF WEBSTER GROVES, MISSOURI

ENVELOPE-MAKING MACHINE

Application filed February 5, 1931. Serial No. 513,502.

This invention relates generally to envelope-making machines, and more specifically to an improved machine of this type which includes an adjustable head which supports the blank-feeding mechanism of the machine, the predominant object of the invention being to provide an envelope-making machine which is capable of being adjusted so that envelopes of different depths, within certain limits, may be fed into the machine by the feeding mechanism thereof with equal facility and accuracy. The improved machine disclosed herein includes also means whereby certain elements of the gumming mechanism may be adjusted transversely of the machine to permit of the gumming of envelope blanks of different widths.

Prior to this invention, envelope-making machines of the general type to which the machine disclosed herein belongs were provided with feeding mechanisms which remained in fixed locations with respect to the remainder of the machines. These feeding mechanisms were adapted to feed envelope blanks of various depths into the machines, and because there was a substantial difference in depth between the largest and the smallest blanks handled by the machines, it was necessary to provide transfer mechanisms which transferred the shorter blanks from the feeding mechanisms to the fixed points at which the envelope blanks entered the blank-folding mechanisms of the machines. One type of transfer mechanism was provided by extending a traveling belt, which constituted a part of the feeding mechanism of the machine, forwardly toward the fixed point at which the blanks entered the folding mechanism of the machine, and while such a transfer mechanism functioned with a fair degree of success, the likelihood was always present that the positions of the envelope blanks would be disturbed while being transferred, with the result that said envelope blanks would be improperly presented to the folding mechanisms of the machines.

The feeding mechanism of my improved machine is supported by a head which is adjustable toward and from the folding mechanism, hence the discharge end of said feed-

ing mechanism may be brought to a point which is so related to the folding mechanism of the machine that each envelope blank, regardless of its depth, is fed directly from the feeding mechanism to the fixed point at which the folding operation is commenced. This arrangement entirely eliminates the intermediate transfer mechanism which heretofore was necessary for the purpose of moving shorter blanks from the feeding mechanism to the folding mechanism of the machine.

In addition to the foregoing, my improved machine includes means whereby elements of the gumming mechanism, when the latter mechanism is carried by the adjustable head which supports the feeding mechanism, may be adjusted transversely of the machine to accommodate envelope blanks of different widths.

Fig. 1 is a fragmentary section of an envelope-making machine constructed in accordance with this invention.

Fig. 2 is an enlarged-sectional view of substantially all of the mechanism illustrated in Fig. 1.

Fig. 3 is a fragmentary detail showing the manner of driving of the feeding mechanism.

Fig. 4 illustrates the mechanism shown in Fig. 3, partly in horizontal section and partly in plan.

Fig. 5 is a view of the machine, partly in horizontal section and partly in plan.

Fig. 6 is a section on line 6—6 of Fig. 2.

Fig. 7 is a section on line 7—7 of Fig. 2.

In the drawings, wherein is shown for the purpose of illustration, merely, one embodiment of the invention, A designates my improved machine generally, said machine including opposed side frame members B, which support the various elements and mechanisms of which the machine is comprised. Adjustably supported by the side frame members B is a head C (Figs. 1 and 2), which likewise comprises a pair of opposed side frame members 1. The lower edges of the side frame members of the head C are provided with inverted V-shaped grooves 2, which extend from end to end of the lower edges of said side frame members, and these grooves receive correspondingly shaped projections 3 formed

on the portions B' of the side frame members B, said projections being arranged substantially horizontally and providing elongated supporting trackways for the adjustable head C.

4 designates an adjusting screw which is supported at one of its ends by a member 5 which is fixed to or formed integral with the side frame members B of the machine, and at 10 its opposite end by an end frame member 6 of the machine. The adjusting screw at its opposite ends is provided with reduced portions 4' which are provided with smooth surfaces, as shown in Fig. 1, these portions 15 being disposed in apertures formed in the member 5 and end frame member 6, respectively, so that the adjusting screw may be subjected to axial rotation. Also, the adjusting screw is provided with shoulders 4^a at the 20 points where the reduced portions 4' join the main screw-threaded portion of the adjusting screw, said shoulders being in substantial contact with the inner faces of the member 5 and end frame member 6, so as to prevent 25 longitudinal movement of the adjusting screw. The screw-threaded portion of the adjusting screw 4 is extended through a screw-threaded aperture 7 formed through an extension 8 fixed to or formed integral 30 with the side frame members 1 of the adjustable head C. Also, the adjusting screw is provided at its outer end with a hand wheel 9 which is fixed thereto and serves to facilitate the rotation of the adjusting screw. 35 It is obvious, in view of the arrangement just described, that if the adjusting screw 4 be subjected to axial rotation the extension 8 will move longitudinally of the screw-threaded portion of the adjusting screw in 40 one or the other direction, depending on the direction of rotation of said adjusting screw. It is likewise plain that the extension 8 is fixed to or formed integral with the side frame members 1 of the head C, hence said 45 head will be subjected to like movement.

Extended transversely of the head C and supported in bearings provided by the opposite side frame members 1 thereof is a shaft 10 which has fixed thereto a pulley or 50 cylinder 11. The side frame members 1 of the head C also support a similar transversely extended shaft 12 which is located above and to one side of the shaft 10, and a like transversely extended shaft 13 which is located below and to the opposite side of said shaft 10. Each of the shafts 12 and 13 has fixed thereto a pulley, the pulley of the shaft 12 being designated by the reference character 14 while the pulley of the shaft 13 is designated by the 55 reference character 15. The side frame members of the adjustable head C support still another transversely extended shaft 16 which supports a pair of spaced apart arms 17. The arms 17 are secured to the shaft 16 by 60 set screws 18, and the ends of said arms op-

posite to the ends thereof which are secured to the shaft 16 support a short shaft 19 on which a pulley 20 is rotatably supported.

The pulleys 11, 14, 15, and 20 are arranged in the same vertical plane, and supported by said pulleys is an endless belt 21. The endless belt 21 passes around the upper portion of the pulley 14 and moves between said pulley 14 and the pulley 11, said belt then passing around substantially one-half of the pulley 11 and moving around the pulley 15. From the pulley 15 the endless belt extends to the pulley 20, around which it passes, and then extends to the pulley 14. The portion of the belt which passes around the pulley 11, of course, contacts with the peripheral face of said pulley as shown clearly in Fig. 1. The pulley 20 about which the endless belt 21 passes is capable of adjustment for the purpose of tightening the belt 21, such adjustment being accomplished by unscrewing the set screws 18 and swinging the pulley-supporting ends of the arms in an arc of a circle about the shaft 16.

The side frame members 1 of the head C of my improved machine are provided with portions 1' which extend upwardly and forwardly at an angle with respect to the remaining portions of said side frame members, and supported at the upper ends of these angular frame portions is a feed table F from which the envelope blanks are fed to the machine. The feed table F comprises a plate 22 which is provided with a cut-out portion 23 and is preferably arranged at a slight angle to the true horizontal. Associated with the plate 22 is a plurality of adjustable guiding members 24 which serve to support a stack of envelope blanks and guide their movement as they are fed into the machine one by one. The guiding members 24 are adjustable so as to provide for the support and guidance of blanks of different dimensions and shapes, but as such adjustable guiding members are quite well known in the art, it will not be necessary to illustrate or describe them in detail in the present application. Supported by the portions 1' of the side frame members 1 and located beneath the plate 22 is a pair of feeding rolls 25 and 26, said feeding rolls being mounted on transversely extended shafts 25' and 26' which are journaled in the portions 1' of the frame members 1. The envelope blanks supported by the feed table F are fed to the feeding rolls 25 and 26 by a suction tube 27 of the type common to paper feeding mechanisms. The suction tube has mechanism associated therewith (not shown) which operates to swing the portion 27' of the suction tube in an arc of a circle to the position indicated by dotted lines in Fig. 1, and to permit such movement the feeding rolls are each arranged in two parts with a space between the inner ends of the opposed sections of each roll. The

spaces between the sections of the rolls 25 and 26 are clearly shown in Fig. 1, wherein said spaces are designated by the reference character S. Also, the feeding rolls are of segmental formation, each of the sections of said rolls comprising an arcuate wall as shown in Fig. 1.

Extended transversely of the head C of the machine and journaled for rotation in the angularly extended portions 1' of the side frame members 1 of said head is a shaft 28, and arranged in alined relation with said shaft 28 is a similarly supported, transverse shaft 29. The shaft 28 has fixed thereto a gumming element 30 of the type ordinarily employed in placing gum on envelope blanks, said element having an arcuate gum-distributing face 30' of such formation as to provide the envelope blanks with layers of gum of the proper shape and extent. The transverse shaft 29 supports a roll 31 which serves as a backing element for the envelope blanks as gum is being applied thereto by the gumming element 30, the peripheral face of said roll 31 and the arcuate gum-distributing face of the gumming element being movable in substantial contact with each other. 32 designates a gum receptacle, and 33 designates a roller which is supported so that its lower portion rotates in the gum within the gum receptacle 32. The peripheral face of the roller 33 contacts with the peripheral face of a gum-transferring roller 34, and this roller 34 is of such diameter that the arcuate gum-distributing face 30' of the gumming element 30 contacts with the peripheral face of said roller 34 during rotation of said gumming element about the axis of the shaft 28. In this manner gum from the gum receptacle is deposited on the arcuate gum-distributing face 30' of the gumming element, the transfer roller 34 transferring gum from the roller 33 to the gum-distributing face referred to.

In order to impart rotary movement to the feeding rolls 25 and 26 as well as to the rolls 31 and 34 and the gum-distributing element of the gumming mechanism, I mount a gear wheel 35 on the shaft 10 which supports the pulley 11. The gear wheel 35 meshes with a smaller gear wheel 36 which is fixedly mounted on the shaft 29 which supports the backing roller 31. In like manner, the shaft 28, which supports the gumming element 30, has fixed thereto a gear wheel 37 which meshes with the gear wheel 36, and a similar gear wheel 37 is mounted on the shaft 34' which supports the gum transfer roller 34. The feeding rolls 25 and 26 are provided with gear wheels 38 and 39, respectively, which mesh with each other, and rotary motion is transmitted from the gear wheel 36 to the gear wheel 39 by an intermediate gear wheel 40. Rotary motion is imparted to the gear wheel 35 associated with the shaft 10 in a manner to be hereinafter set

forth, and this motion is transmitted by the train of gearing just described to the feeding rolls 25 and 26, and to the rotating elements of the gumming mechanism, in a manner which is perfectly obvious.

In order to conduct the envelope blanks from the feeding rolls 25 and 26 to a point where said envelope blanks will pass between the gumming element 30 and backing roller 31, I employ an inclined support 41. Also, I provide a similar inclined support 42 for conducting the envelope blanks from the position of the gumming element 30 and roller 31 to the point where said blanks are engaged by the pulley and endless belt 21.

In the operation of the feeding and gumming mechanism of my improved machine, the envelope blanks are removed from the bottom of the stack of blanks supported by the feed table F by the suction tube 27, said blanks being drawn through the opening 23 and being presented to the feeding rolls 25 and 26 so that they pass between said feeding rolls and are fed forwardly by the arcuate segmental walls thereof. The blanks then pass from the feeding rolls 25 and 26 to the inclined support 41 along which said blanks pass to the gumming mechanism. The gumming operation is performed as the blanks pass between the arcuate gum-distributing face 30' of the gumming element 30 and the peripheral face of the roller 31, and after such gumming operation has been performed the blanks move downwardly along the inclined support 42 to a point where said blanks are gripped between the pulley 11 and the endless belt 21. The blanks which have been gripped as described are carried around the periphery of the pulley 11 in the direction indicated by the arrow in Fig. 1, said blanks being tightly gripped at all times during such movement between the pulley 11 and the endless belt 21. When the blanks passing around the pulley 11 reach the position of the pulley 15 they pass from between the peripheral face of the pulley 11 and the endless belt and are delivered to the folding mechanism of the machine in a manner which will be hereinafter set forth.

It is important to note that preferably all of the feeding mechanism and the gumming mechanism of the machine are carried by the adjustable head C of the machine, hence, by adjusting said head with the aid of the adjusting screw 4 in the direction of the double headed arrow in Fig. 1, the point X at which the blanks pass from between the pulley 11 and the endless belt 21 may be so located that said blanks will be delivered directly to the folding mechanism of the machine. This is the predominant feature of the invention, and said feature entirely eliminates the intermediate transfer mechanism formerly employed for moving the shorter blanks from the feeding mechanism to the folding mechanism.

Also, an important feature of the invention is the provision of gumming elements 30 which are adjustable transversely of the head C, said gumming elements being secured to the shaft 28 by means of set screws 28' which permit of the adjustment referred to. By providing for adjustment of the gumming elements 30 transversely of the head C, envelope blanks of different widths may be gummed by the gumming mechanism.

The envelope machine illustrated in the drawings forming parts of this application includes folding mechanism F which is operable to fold the blanks in producing completed envelopes therefrom. The particular folding mechanism illustrated is one of a number of folding mechanisms which are in use at the present time, and as the construction and operation of the folding mechanism illustrated and the other folding mechanisms referred to are very well known by persons familiar with the art, it will not be necessary to describe the folding mechanism illustrated in the drawings in detail. It will be necessary, however, to describe the illustrated folding mechanism sufficiently to enable one to understand the relation of the feeding and gumming mechanisms of the machine with respect thereto, and the description of the folding mechanism of the machine will be only of such scope as to accomplish this purpose.

The folding mechanism F of the machine A comprises a pair of oppositely disposed plates 50 which serve to fold the side flaps s of the envelope blank E (Fig. 5). These plates 50 are adjustably fixed to carrier elements 51 which are pivotally attached at 51' to bell-crank levers 52. Each of the bell-crank levers 52 has rotatably associated therewith at its forward portion a roller 53 which contacts with the top face of a fixed cam 54, said top face of each of said fixed cams comprising a lower face portion 54^a, an upper face portion 54^b, and an inclined face portion 54^c which joins the face portions 54^a and 54^b, as shown in Fig. 7. Associated with each of the bell-crank levers 52 is a member 55 which is guided for vertical movement by guiding elements 56, said member 55 being pivoted at its upper end to the associated bell-crank lever 52, and being provided at its lower end with a roller 57 which contacts with a cam 58 mounted on a shaft 59. The bell-crank levers 52 are provided with coil springs 60 which tend to draw the substantially horizontal portions of said bell-crank levers downwardly. Also, coil springs 61 are attached to the carriers 51 and to fixed parts of the machine in a manner to cause the rollers 53 associated with said carriers to be drawn downwardly against the top faces of the fixed cams 54.

The folding mechanism F includes also a plate 62 (Figs. 2 and 7) which acts as a

support for the blanks during the folding operations, said plate being supported in a fixed position by the fixed element 63 of the machine. Arranged above the plate 62 is a folding plate 64, said folding plate being fixedly maintained in slightly spaced relation with respect to the plate 62, as shown in the two views of the drawings referred to.

Fixed to a rockable shaft 65 (Fig. 2) is a pair of substantially vertically disposed arms 66, the upper ends of which are movable as suggested by the arrow in Fig. 2 when the rockable shaft 65 is rocked. Pivot to the arms 66 at the locations of the trunnions 67 which extend into openings formed in the arms 66 is a transversely extended bar 68 to which is rigidly attached a forwardly extended folding plate 69. The folding plate 69 is preferably curved downwardly and is movable with the arms 66 when the upper portions thereof move in the direction indicated by the arrow in Fig. 2. Fixed to one of the trunnions 67 is an arm 70, which is provided with a roller 72, said roller being arranged in rolling contact with the top face of an arm 73 which is pivoted at 74 to a fixed part of the machine. The arm 73 has associated therewith a roller 75 which contacts with a cam 76 mounted on a shaft 77 extended transversely of the machine. The shaft 77 has fixed thereto a feeding roller 78, and fixedly mounted on a transverse shaft 79 aligned vertically with the shaft 77 is a segmental feeding element 80. The feeding roller 78 and the segmental feeding element 80 are so arranged that the peripheral faces thereof are in substantial contact with each other, so that the envelopes will be fed through the machine by said feeding rollers and feeding element. Also, these elements serve to cause certain of the flaps of the envelopes to adhere to each other because of gum applied thereto.

In the operation of the folding mechanism F of the machine, the plates 50 are moved inwardly by the cams 58, and simultaneous with such inward movement the inner ends of said plates are moved upwardly due to the rollers 53 (Fig. 7) rolling on the irregular top faces of the fixed cams 54. This movement of the plates 50 causes the side flaps s of the envelope blank E to be folded upwardly and inwardly over the folding plate 64 in the well-known manner. Immediately following such folding of the side flaps s of the envelope blank E the cam 76 elevates the outer end portion of the arm 73, with the result that like upward movement will be imparted to the arm 70 through the instrumentality of the roller 75. The arm 70 is fixed to one of the trunnions 67, and when said arm is elevated as described, the bar 68 will be pivoted about the trunnions, whereby the outer end portion of the folding plate 69 will be moved upwardly in

- an arc of a circle. This movement of the folding plate 69 will result in the flap *e* of the envelope blank *E* being subjected to like upward movement. During the upward movement of the outer end portion of the folding plate 69 the upper end portions of the arms 68 will be moved in the direction indicated by the arrow in Fig. 2 in response to rocking movement imparted to the shaft 65 by suitable mechanism (not shown), and by virtue of the upward and longitudinal movement of said folding plate 69 the flap *e* of the envelope blank *E* is folded upwardly and over the fixed folding plate 64.
- During passage thereof through the machine the movement of each envelope blank is arrested to permit the folding operation to take place, and for arresting the movement of the blanks I employ a pair of stop elements 45 (Figs. 2 and 7). The stop elements 45 are each in the form of a substantially L-shaped member which is pivoted to a supporting member 46 at the point designated by the reference character 47. At the upper portions of the stop elements portions thereof are arranged substantially parallel and in overlapping relation, as shown in Fig. 7, and another portion 45' of each stop element extends downwardly from the horizontal portion thereof. Attached to the oppositely disposed stop elements 45 above the pivotal points 47 thereof is a coil spring 48 which tends to move the lower end portions of said stop element in a direction away from each other. 49 designates adjustable stops which serve to limit the amount of movement of the stop elements 45.
- Supported by suitable bearings 81 is a transversely extended shaft 82 to which an arm 83 is fixed, said arm 83 being arranged beneath the overlapping portions of the stop elements 45, as shown in Figs. 2 and 7. The transverse shaft 82 has fixed to it a spring-loaded arm 84 which is provided at the end opposite to the end thereof which is attached to the shaft 82 with a roller 85. The roller 85 contacts with the peripheral face of a cam 86 which is fixed on the drive shaft 87 of the machine, said cam being so shaped as to cause the roller 85 and the end portion of the arm 84 at which said roller is located to move upwardly in an arc of a circle.
- In the operation of the stop elements 45 the high portion of the cam causes the roller 85 and outer end portion of the arm 84 to be elevated, with the result that the outer end portion of the arm 83 is moved downwardly. This will permit the coil spring 48 to draw the portions of the stop elements 45 above the pivotal points 47 thereof inwardly, so as to cause the lower portions of said stop elements to move away from each other, the inner end portions of the horizontal portions of the stop elements moving downwardly during such movement of said stop elements. When the lower portions of the stop elements 45 are separated as described, the envelope blanks may pass between said lower portions of said stop elements and continue their passage through the machine. However, when the low portion 86' of the cam 86 is in contact with the roller 85, said roller and the outer end portion of the arm 84 will be depressed, with the result that the outer end portion of the arm 83 will be elevated. Such elevated position of the arm 83 will cause the inner end portions of the horizontal portions of the stop elements to be elevated, with the result that the lower end portions of the vertical portions 45' of the stop elements 45 will be drawn inwardly, whereby said lower end portions of the stop elements will be in the path of travel of the envelope blanks so as to interrupt the movement thereof.
- It is plain, therefore, that during the operation of the machine the lower portions of the stop elements 45 periodically move inwardly toward each other to stop an envelope blank which is approaching said stop elements, and that during such interruption of the movement of the envelope blank said blank is folded, as already explained. After each envelope blank has been folded, it again resumes its movement through the machine by virtue of the operation of a rotary segmental feeding element *f* which engages the blank between the curved feeding face thereof and the plate 62 in a manner to feed said blank between the roller 78 and the segmental feeding element 80, whereby the movement of said blank through the machine is continued, said blank being guided during such movement by an element 87 which is so arranged as to feed the blank between feeding rollers 88 and 89 which are mounted on the drive shaft 87 and a shaft 90, respectively.
- The drive shaft 87 has mounted thereon a gear wheel 91 which meshes with an intermediate gear wheel 92. The intermediate gear wheel 92 in turn meshes with a gear wheel 93, which is fixed to the shaft 77 on which the feeding roller 78 is mounted, and the gear wheel 93 meshes with a similar gear wheel fixed to the shaft 79 on which the segmental feeding element 80 is arranged. In this manner motion is transmitted from the drive shaft 87 to the feeding means provided by the roller 78 and segmental feeding element 80. Also, the segmental feeding element *f* is subjected to rotary motion by suitable gear wheels *f'*.
- The drive shaft 87 also has fixed to it a bevel gear 94 which meshes with a similar bevel gear 95. The bevel gear 95 is fixed to a vertically supported shaft 96, which has fixed thereto at its upper end a bevel gear 97, and this latter bevel gear meshes with a like bevel gear 98 which is fixed to a

horizontally supported shaft 99. The horizontal shaft 99 serves to transmit motion to the feeding mechanism of the machine, said shaft having a bevel gear 100 associated therewith which meshes with a similar bevel gear 100' fixed to the shaft 10 on which the pulley 11 of the feeding mechanism is mounted. The bevel gear 100 is feathered to the shaft 99 so that it may move longitudinally with respect thereto when the head 10 C is adjusted, said bevel gear 100 being engaged by an element 101 (Fig. 1) on the head C, which permits the bevel gear to rotate with the shaft 99 but causes said bevel gear to move with said head C.

15 From the foregoing specification it is plain that the preferred form of the improved envelope-making machine disclosed herein includes a folding mechanism of any desired form and a suitable feeding mechanism, said

20 feeding mechanism being adjustable toward and from the folding mechanism so that envelope blanks of various depths may be operated on by the machine with convenience and facility. While the above describes the preferred form of my invention, I do not

25 wish to be limited to this precise arrangement, as substantially the same results may be obtained by maintaining the feeding mechanism of the machine in a fixed location and adjusting the folding mechanism toward and from said feeding mechanism. In its broadest aspect, therefore, my invention involves providing an envelope-making ma-

30 chine which includes a feeding unit and a folding unit, one of which is adjustable toward and from the other to permit of envelope blanks of different depths being acted on by the machine.

35 40 I claim:

1. An envelope-making machine comprising blank-feeding mechanism, blank-folding mechanism, stop means for arresting movement of the envelope blanks to the blank-folding mechanism, and means for providing for the adjustment of one of said mechanisms toward and from said stop means to permit the machine to produce envelopes from blanks of different depths.

45 50 55 2. An envelope-making machine comprising blank-folding mechanism, blank-feeding mechanism, stop means for arresting movement of the envelope blanks to the blank-folding mechanism, and means providing for the adjustment of said blank-feeding mechanism toward and from said stop means to permit the machine to produce envelopes from blanks of different depths.

60 65 3. An envelope-making machine comprising blank-folding mechanism, blank-feeding mechanism, stop means for arresting movement of the envelope blanks to the blank-folding mechanism and means providing for the adjustment of said blank-feeding mechanism toward and from said stop means to

permit the machine to produce envelopes from blanks of different depths, said means comprising a movable element providing a support for the feeding mechanism, and means for subjecting said movable element to adjustment.

4. An envelope-making machine comprising blank-folding mechanism, blank-feeding mechanism, stop means for arresting movement of the envelope blanks to the blank-folding mechanism and means providing for the adjustment of said blank-feeding mechanism toward and from said stop means to permit the machine to produce envelopes from blanks of different depths, said means comprising a movable element providing a support for the feeding mechanism, and screw-threaded means for subjecting said movable element to adjustment.

5. An envelope-making machine comprising blank-folding mechanism, blank-feeding mechanism, stop means for arresting movement of the envelope blanks to the blank-folding mechanism and means providing for the adjustment of said blank-feeding mechanism toward and from said stop means to permit the machine to produce envelopes from blanks of different depths, said means comprising a movable element providing a support for the feeding mechanism, guiding means for guiding the movement of said movable element, and screw-threaded means for subjecting said movable element to adjustment.

6. An envelope-making machine comprising blank-folding mechanism, blank-feeding mechanism, means providing for the adjustment of said blank-feeding mechanism toward and from said blank-folding mechanism to permit the machine to produce envelopes from blanks of different depths, said means comprising a movable element providing a support for the feeding mechanism and means for subjecting said movable element to adjustment, and gumming mechanism supported by and movable with said movable element.

7. An envelope-making machine comprising blank-folding mechanism, blank-feeding mechanism, means providing for the adjustment of said blank-feeding mechanism toward and from said blank-folding mechanism to permit the machine to produce envelopes from blanks of different depths, said means comprising a movable element providing a support for the feeding mechanism and means for subjecting said movable element to adjustment, and gumming mechanism supported by and movable with said movable element, said gumming mechanism including element adjustable transversely of the machine to provide for gumming envelope blanks of different widths.

8. An envelope-making machine comprising a blank-folding mechanism, blank-feed-

ing mechanism, means providing for the adjustment of said blank-feeding mechanism toward and from said blank-folding mechanism to permit the machine to produce envelopes from blanks of different depths, said means comprising a movable element providing a support for the feeding mechanism and means for subjecting said movable element to adjustment, gumming mechanism supported by and movable with said movable elements, and a feed table for feeding envelope blanks to the feeding mechanism.

9. An envelope-making machine comprising blank-folding mechanism, blank-feeding mechanism, means providing for the adjustment of said blank-feeding mechanism toward and from said blank-folding mechanism to permit the machine to produce envelopes from blanks of different depths, said means comprising a movable element providing a support for the feeding mechanism and means for subjecting said movable element to adjustment, gumming mechanism supported by and movable with said movable elements, and an adjustable feed table for feeding envelope blanks to the feeding mechanism.

10. An envelope-making machine comprising blank-folding mechanism, blank-feeding mechanism, means providing for the adjustment of said blank-feeding mechanism toward and from said blank-folding mechanism to permit the machine to produce envelopes from blanks of different depths, said means comprising a movable element providing a support for the feeding mechanism and means for subjecting said movable element to adjustment, gumming mechanism supported by and movable with said movable elements, and a feed table carried by said movable element for feeding envelope blanks to the feeding mechanism.

11. An envelope-making machine comprising blank-folding mechanism, blank-feeding mechanism, means providing for the adjustment of said blank-feeding mechanism toward and from said blank-folding mechanism to permit the machine to produce envelopes from blanks of different depths, said means comprising a movable element providing a support for the feeding mechanism and means for subjecting said movable element to adjustment, gumming mechanism supported by and movable with said movable element, and an adjustable feed table carried by said movable element for feeding envelope blanks to the feeding mechanism.

12. An envelope-making machine comprising blank-folding mechanism, blank-feeding mechanism, said blank-feeding mechanism including an endless feeding belt supported for operation on pulleys, stop means for arresting movement of the envelope blanks to the blank-folding mechanism, and means providing for the adjustment of said blank-feeding mechanism toward and from said

stop means to permit the machine to produce envelopes from blanks of different depths.

13. An envelope-making machine comprising blank-folding mechanism, blank-feeding mechanism, said blank-feeding mechanism including an endless feeding belt supported for operation on pulleys, one of said pulleys being relatively large with respect to the other belt-supporting pulleys and the envelope blanks being fed by the feeding mechanism being moved between the circumferential face of said large pulley and said endless belt, and means providing for the adjustment of said blank-feeding mechanism toward and from said blank-folding mechanism to permit the machine to produce envelopes from blanks of different depths.

14. An envelope-making machine comprising blank-folding mechanism, blank-feeding mechanism, stop means for arresting movement of the envelope blanks to the blank-folding mechanism, means providing for the adjustment of said blank-feeding mechanism toward and from said stop means to permit the machine to produce envelopes from blanks of different depths, and driving means for driving said feeding mechanism, said feeding mechanism being adjustable relative to said driving means.

15. An envelope-making machine comprising blank-folding mechanism, blank-feeding mechanism, stop means for arresting movement of the envelope blanks to the blank-folding mechanism, means providing for the adjustment of said blank-feeding mechanism toward and from said means to permit the machine to produce envelopes from blanks of different depths, and driving means for driving said feeding mechanism, said driving means including a shaft with respect to which said feeding mechanism is adjustable.

In testimony that I claim the foregoing I hereunto affix my signature.
